INVENTOR,
Jesse Collings,
BY
C. G. Siggers.
ATTORNEY.

UNITED STATES PATENT OFFICE.

JESSE COLLINGS, OF RICHMOND, ENGLAND.

SEAL FOR USE IN PACKING OR FOR OTHER LIKE PURPOSES.

1,410,998.

Specification of Letters Patent. Patented Mar. 28, 1922.

Application filed July 10, 1920. Serial No. 395,377.

(GRANTED UNDER THE PROVISIONS OF THE ACT OF MARCH 3, 1921, 41 STAT. L., 1313.)

To all whom it may concern:

Be it known that I, JESSE COLLINGS, subject of His Majesty the King of England, and resident of Richmond, in the county of 5 Surrey and Kingdom of England, have invented certain new and useful Improvements in Seals for Use in Packing or for other like Purposes, (for which I have filed an application in Great Britain dated March 10 16, 1917, Patent No. 112,853,) of which the following is a specification.

This invention relates to seals for use in packing or for other like purposes, such as the sealing up of mail or other bags, and in 15 which a tube, through which the string, cord or wire is passed, is inserted in a holder and crushed to prevent withdrawal of said string, cord or wire.

The object of the present invention is to 20 provide an improved seal of this type which will be simple in construction, cheap to produce, and reliable and safe in practice.

The invention will now be described with 25 reference to the accompanying drawings in which:—

Figure 1 is a plan of a seal constructed in accordance with the invention,

Figures 2 and 3 are side and front edge views, respectively, of same.

30 Figure 4 is a view similar to Figure 1 but showing the tube crushed.

Figure 5 is an enlarged sectional elevation on the line 5—5 of Figure 4, and

35 Figures 6 and 7 are views similar to Figures 4 and 5 but illustrating a slight modification and both the tube and the punched-out sections crushed.

According to the present invention, and 40 as illustrated in Figures 1 to 7, the improved

seal comprises a tag, *a* which term is used to broadly cover any form of plate or holder of thin sheet metal and is adapted to receive or have stamped thereon any desired trade advertisement or designating mark.

45 At a suitable part, conveniently along one side thereof, the said tag is formed with a plurality of alternatively opposed curved or indented portions *b* provided by punching out small strips or sections of the metal alternatively from opposite sides. These

50 curved or indented portions *b* thus somewhat resemble corrugations and jointly provide a corrugated channel or hole *c* through the said tag and in the same plane. An inner tube or sleeve *d* of folded metal is next in-

serted through the corrugations, and the parts are so formed that the said tube will be held in place therein by friction or by expanding or bevelling the ends of the tube after insertion. 60

In use, the string, cord or wire *e* is passed through the inner tube *d* and the latter and/or the corrugations *b* of the tag is or are crushed by means of a suitable tool, such as a pair of pliers, in a wave or corrugated form, for instance as shown in Figures 5 and 7, so as to cause the waves or corrugations of the tube to be pressed onto or together with the raised corrugations formed in the tag, or thereabouts, thus causing the parts 70 to be effectively interlocked. In Figures 4 and 5 the tube *d* is engaged and crushed at *f* between each two adjacent corrugations *b* on each side and pressed onto all of the corrugations, whilst in Figures 6 and 7 the corrugations *b* are crushed at *g* and pressed together with the tube. 75

It will thus be understood that the crushing of the tube *d* prevents the string, cord or wire *e* passed through it being withdrawn, whilst the corrugated channel in the tag effectively prevents any tampering with the tube, thus providing important additional security. 80

What I claim is:—

1. A seal for use in packing or other like purposes, comprising a tag, formed with a plurality of alternately opposed curved or indented strips to provide a corrugated or irregular channel, and a tube inserted in said channel and held by said strips, said tube being pressed into an irregular formation to prevent the withdrawal of a cord or wire passed through said tube. 85

2. A seal for use in packing or for other like purposes, comprising a tag, formed with a plurality of alternately opposed curved or indented strips to provide a corrugated or irregular channel, and a tube inserted in said channel and held by said strips, said tube being pressed between and onto the curved or indented strips for the purpose of locking the tube in the channel. 95

3. A seal for use in packing or for other like purposes, comprising a tag, formed with a plurality of alternately opposed curved or indented strips to provide a corrugated or irregular channel, and a tube inserted in said channel and held by said strips, said tube being pressed into an irregular formation to 105 110

prevent the withdrawal of a cord or wire passed through said tube, the ends of the irregularly formed tube being mutilated to prevent displacement of the tube from the channel.

4. A seal for use in packing or other like purposes comprising a tag formed with a plurality of alternately opposed curved or indented strips to provide a corrugated or 10 irregular channel, and a tube inserted in

said channel and held by said strips, said tube being pressed from opposite sides of the tag onto the alternately opposed or indented strips to prevent the withdrawal of a wire passed through said tube, the pressed or flattened portion of the tube preventing displacement of the tube from the channel. 15

In testimony whereof I have hereunto signed my name.

JESSE COLLINGS.
